DESIGN FOR A PLASTIC TUBE OR SIMILAR ARTICLE

Edmund H. Tyson, Caldwell, N. J., assignor, by mesne assignments, to E. I. du Pont de Nemours & Company, Wilmington, Del., a corporation of Delaware

Application July 15, 1936, Serial No. 63,862

Term of patent 7 years

To all whom it may concern:

Be it known that I, Edmund H. Tyson, a citizen of the United States and a resident of Caldwell, in the county of Essex and State of New Jersey, have invented a certain new, original, and ornamental Design for a Plastic Tube or Similar Article, of which the following is a specification, reference being had to the accompanying drawing, forming part thereof

In the accompanying drawing:

The figure is a plan view of a plastic tube or similar article showing my new design.

The ornamentation of the plastic tube or similar article comprises alternately colored rectangular areas, containing light reflecting particles, arranged in spiral relationship relative to the length of the tube.

I claim:—

The ornamental design for a plastic tube or similar article, substantially as shown and described.

EDMUND H. TYSON.
